UNITED STATES PATENT OFFICE.

ANDREW L. RIKER, OF BRIDGEPORT, CONNECTICUT, ASSIGNOR TO THE "LOCOMOBILE" COMPANY OF AMERICA, OF NEW YORK, N. Y., A CORPORATION OF WEST VIRGINIA.

INTERNAL-COMBUSTION ENGINE.

1,109,637.

Specification of Letters Patent.

Patented Sept. 1, 1914.

Application filed June 29, 1903. Serial No. 163,500.

To all whom it may concern:

Be it known that I, ANDREW L. RIKER, a citizen of the United States, residing at Bridgeport, in the county of Fairfield and State of Connecticut, have invented an Improvement in Internal-Combustion Engines, of which the following description, in connection with the accompanying drawings, is a specification, like letters on the drawings representing like parts.

My invention aims to provide an improved internal combustion engine, one which, among other features, will be self-starting, reversible, and capable of being operated at any desired speed and containing provision for automatically cutting off the power mixture or fluid at any desired point or points whereby to secure the most effective and economical use thereof.

My invention will be best understood from a description of the best embodiment thereof now known to me and shown in the accompanying drawings, wherein—

Figure 1, in vertical longitudinal section shows an engine illustrating one embodiment of my invention; Fig. 2, a vertical cross section on the dotted lines 2—2, Fig. 1; Fig. 3, a top or plan view of the engine shown in Figs. 1 and 2; Fig. 4, a detail illustrating a portion of the inlet valve actuating cam; Fig. 5, an end view of Fig. 4; Fig. 6, a sectional detail illustrating the co-operating spark making and breaking contacts; Fig. 7, a sectional detail of one of the inlet valve seats and its valve; and, Fig. 8, a view illustrating a typical motor vehicle to which my improved engine is particularly adapted the engine being shown in position therein.

In the particular embodiment of my invention selected for illustration herein and shown in the drawing, referring first to Figs. 1 and 2, the engine is provided with four vertically arranged cylinders, *a*, *a*, *a*, and *b*, shown as, though not necessarily, formed in one and the same casting, *A*, which may be provided with a suitable cooling chamber, *A'*, through which a cooling medium may be circulated, in usual or desired manner. This cylinder casting, *A*, is shown mounted upon a crank casting, *B*, conveniently formed in two parts, marked respectively *B* and *B'*, said parts being separated horizontally and secured one to the other in suitable manner. One of the crank chamber parts, as, for instance, that marked *B*, is provided

with means, as the laterally extended arms or brackets, *B*², Fig. 2, by which to support the said engine upon a suitable frame, as *B*³, which may be a part of the frame of a motor vehicle.

The cylinders, *a*, *b*, contain respectively trunk pistons, *a'*, *b'*, the wrist pins whereof are connected by suitable connecting rods, *a*², *b*², with the cranks *a*³, *b*³, of the crank-shaft, *C*, journaled in suitable bearings in the crank casting and, preferably formed one half each in the two parts of the said casting.

The cylinders, *a*, herein shown as three in number, in the present embodiment of my invention, constitute the working or power cylinders, while the cylinder *b* is used as an air compression cylinder, although it will be evident that the invention is in no wise restricted to any particular number of cylinders, whether one or more, used either as working or compression cylinders.

Each of the working cylinders, *a*, is provided with an inlet port, *d*,—shown best in Fig. 7,—surrounded by a valve seat, shown 80 as conical and formed in the removable valve seat, *d'*, in the cylinder head. Upon this seat *d'*, in turn is seated a hood, *d*², each hood, see Fig. 3, being formed integrally with and as a branch of the main supply 85 pipe, *d*³, which supplies compressed air to the cylinders from the compression reservoir or tank, *D*. The air pressure in the reservoir, *D*, is usually maintained at about 300 lbs., while the desired working pressure for 90 admission to the cylinders, should be ordinarily at or about 90 lbs., and to obtain this reduction, I may employ a usual pressure reducing valve, *D'*, Fig. 3, the admission of 95 air under pressure from the reservoir to and through this valve to the engine being controlled by a usual throttle valve, *D*², under the control of a throttle lever, *D*³, which may be controlled from any suitable or desired point.

Returning now to Fig. 7, each inlet is controlled by a puppet valve, *d*⁴, the stem *d*⁵ of which is encircled by a suitable spring, *d*⁶, see Fig. 1, which maintains the said valve normally seated; it being unseated or opened 105 at the proper times by positive operating means, to be described.

Referring to Fig. 1, each of the working cylinders has an exhaust opening *e*, surrounded by a valve seat, which, with its 110

valve e' , is constructed and operated precisely as described with reference to the inlet valve seats and valves, Fig. 7, similar index reference letters e , indicating parts 5 corresponding to those shown in Fig. 7.

Each of the exhaust ports, e , communicates with the interior of a hood e^2 ; said hood, see Fig. 3, being formed integral with, and as a branch of the main exhaust pipe 10 e^3 , which discharges through a suitable branch, e^4 , leading to any desired point.

Referring to Fig. 2, the crank casting part, B, has at its opposite sides, offset portions or chambers, f , g , in which are respectively arranged the cam shafts, f' , and g' , arranged parallel with the crankshaft, C, and journaled in suitable bearings formed in the crank casting. Each of these offset chambers, f , g , has a removable cover portion, f^2 , g^2 , to permit access to the inclosed parts. These cam shafts are provided respectively with gear wheels, f^3 , g^3 , which mesh with and are driven by a gear wheel, F, fast upon the main crankshaft, so that 25 rotation of the latter causes corresponding rotation of the cam shafts.

Referring to Fig. 4, the cam shaft, f' , which is herein used as the inlet cam shaft,—that is, to control the inlet valves,—30 is provided opposite each cylinder, a , with a pair of oppositely tapering skew cam surfaces, f^4 , f^5 and coöperating with each pair of these cam surfaces is a roller, f^6 , upon the lower end of the valve actuating rod, f^7 , 35 mounted to slide vertically in suitable bearings and at its upper end standing under one end of a horizontal lever, f^8 , fulcrumed at f^9 , upon the inlet supply pipe, d^8 , and overlying at its opposite end the valve stem, d^9 , 40 whereby when the said valve rod, f^7 , is raised, the valve stem will be depressed and its valve unseated. The valve actuating rod, f^7 , is maintained normally depressed, with its roller, f^6 , in operative contact with the 45 cam shaft or its cam surfaces by a spring, f^{10} , shown best in Fig. 2.

With the cam shaft, f' , in the position shown in Figs. 2, 4, and 5, the roller f^6 , bears upon the said shaft at a point between the 50 two skew cam surfaces, f^4 , f^5 ; consequently, rotation of the said cam shaft will exercise no effect whatever upon the roller, f^6 , its valve operating rod and valve. If, however, the cam shaft, f' , be moved in the direction 55 of the arrow, Fig. 4, its driving gear, f^3 , being splined thereon to permit such movement, the skew cam, f^4 , will be brought more or less under the roller, f^6 , and according to the extent of such longitudinal movement 60 of the cam shaft, will at each rotation of said shaft lift the roller f^6 , and open the valve controlled by it to a degree determined by the particular part of the tapered cam, which is caused to act upon and lift 65 the roller.

The cam f^4 , is positioned so as to govern the inlet valves with the engine running in a forward direction, that is, in the direction of the arrow, Fig. 2, and the higher the point upon the said cam, which acts upon 70 the roller, f^6 , the wider will be the valve opening and the later the cut-off.

The cam f^8 , on the other hand, is offset somewhat or askew relative to the cam f^4 , and is properly positioned to control the 75 inlet valve movement for running the engine in a reverse direction; it operating otherwise as the cam surface f^4 to vary the degree of opening and period of cut-off of its valve during the reverse operation of the 80 engine.

By sliding the cam shaft f' axially, the cam f^4 may be brought into position to run the engine forward, the cam f^8 brought into position to run the engine backward; or, the 85 shaft may be brought to an intermediate position indicated in Fig. 4, in which it will not move the inlet valve, thus holding the engine at rest. To accomplish this axial shifting movement of the inlet cam shaft, 90 said shaft is provided, see Fig. 1, with a circumferentially grooved collar, f^{11} , which, see Fig. 8, is engaged by a yoke upon the lever controller, f^{12} , pivoted at f^{13} , and controlled, as to its position, by a usual notched quadrant, f^{14} , with a coöperating spring controlled latch upon the lever. By means of this lever, the cam shaft may be positioned as desired, to cause any desired speed or direction of the engine. 100

Referring to Fig. 2, the exhaust cam shaft g' opposite each cylinder a , has a suitable cam g^3 which coöperates with a roller, g^6 , upon the forked end of the exhaust valve stem g^7 , controlled by a spring g^{10} , and acting at its upper end upon a lever g^8 , fulcrumed at g^9 , and overlying at its inner end one of the exhaust valve stems e^5 . Rotation of the exhaust cam shaft g' thus controls the opening and closing of the exhaust valves, 110 which opening and closing may, however, remain constant, regardless of the point of cut-off of the inlet valves or the speed of the engine.

Each cylinder a about midway its length 115 and at the end of the stroke of the upper end of the piston therein, is provided with a supplemental exhaust g^{11} , which is merely a port in the wall of the cylinder communicating through a branch g^{12} with the main exhaust branch pipe e^4 , said supplemental exhaust port being opened and closed by the piston itself in its movements within the cylinder. 120

The air compression piston b' in the cylinder b , draws its supply through the spring controlled self-opening valve, b^4 , and delivers its compressed air to the reservoir D, past the spring pressed discharge valve b^6 in the pipe b^6 leading to said reservoir. 125 130

The gasoline or other hydro-carbon fuel from any suitable source, under pressure, as from a pump typified at P, is forced to the engine through a pipe h, Fig. 1, provided with a branch h', leading to each working cylinder, and, see Fig. 7, each branch h' communicates with a groove turned or cored in the valve seat d' of the inlet valve, so that when the said valve is seated, escape of fuel from the branch pipes h' is cut off; but when the said valve is open, fuel may escape from the said branch pipes between the valve and its seat, and is, of course, being immediately atomized by the inrushing air simultaneously admitted through said port and in contact therewith.

Referring to Fig. 8, the supply of hydro-carbon or other fuel, through the pipe h, is controlled by a throttle, typified at T.

The operation of the engine may be described as follows: assuming the reservoir D to contain already air under pressure, say of 300 lbs. to the square inch, which remains from the last or previous operation of the engine, to start the engine, the throttle valves D¹, T, are opened to permit air under pressure and fuel to pass to one of the three working cylinders a, whose inlet valve d⁴, is for the moment open; and this compressed air acts like steam in a steam engine to start the engine. As soon as the engine is started, the compression piston b' renews and maintains the air pressure in the reservoir D, which at each rotation of the crankshaft C is permitted to enter the several working cylinders a, and as it enters each cylinder, atomizes the fuel from the branch pipes h', forming a combustible mixture, which, at the proper moment in each cylinder, is ignited by suitable sparking or other means in any usual or well-known manner.

When the piston in any cylinder reaches the end of its downward stroke, the supplementary port g¹¹, is uncovered and permits the bulk of the spent or burned gases to escape, whatever gases remain in the cylinder during the upward or return stroke of the piston escaping through the positively opened and controlled exhaust valve e⁴, in the head of the cylinder. By this means I obtain a very free exhaust when the piston reaches the limit of its downward stroke, leaving practically no back pressure during the return stroke of the piston, yet by means of the positively controlled exhaust valve in the head of the cylinder, I may regulate the closure of the exhaust and thus regulate the compression to any desired extent necessary to insure proper running of the engine.

The action of the exhaust valves obviously may be varied as desired by shifting the individual cams g⁸ of the cam shaft or by changing the position of the latter relatively to the driving gear.

In the present instance, for a sparking or

igniting means, I have provided each cylinder with a usual spark plug m, the current through which is produced at the required intervals, by suitable means, as, for instance, see Fig. 6, the rotatable contact m' on the inlet cam shaft f' and co-operating with the several fixed contacts m², one for and connected with the spark plug of each cylinder a. The fixed contacts m² mounted in a rotatable shell m³, which, see Fig. 2, has its hub provided with a spiral groove m⁴, engaged by a fixed stop m⁵ on the gear casing or other fixed part of the engine. Thus, when the inlet cam shaft m' is moved axially in one or the other direction to effect reversal of the engine, the same movement will, through the spiral groove m⁴ cause partial rotation of the contact carrying shell m³ to position the contacts properly for operating the engine in the new direction, as well as to maintain the time of sparking always in proper relationship to the cut-off and speed of the engine. Thus, every change in the position of the cam shaft for a new cut-off brings its corresponding changes in the time of sparking.

The engine described is self-starting, because it always has at hand air under pressure in the reservoir D sufficient to start the engine precisely as steam is used to start a steam engine. When, after a long period of disuse the reservoir D is exhausted, its pressure may be renewed, as by a hand pump o, Fig. 8, provided for the purpose. Ordinarily, however, air under pressure in the reservoir D will remain for a long period of time.

The engine also is self-reversing, like a steam engine; it being provided with means for controlling its valves, which, with a pressure constantly at hand for starting the engine, furnishes what is necessary for starting in either direction, at will.

The control provided for the inlet cam shaft f', whereby its position may be determined at will, furnishes means for varying the cut-off,—that is, the period of admission of the combustible,—to the cylinders precisely as steam is controlled in a steam engine with an automatic cut-off valve motion, making it possible to operate my improved engine with a high degree of economy and to regulate its speed by cut-off as well as by throttling at the valve D².

I thus obtain in an internal combustion engine substantially all the characteristic features of a modern steam engine, thereby greatly enlarging the field of usefulness of internal combustion engines.

Referring to Fig. 8, I have illustrated my engine mounted in usual position upon a typical motor vehicle comprising usual wheels, a frame c and body c'. The engine crankshaft, by reason of the construction of the engine, is geared directly to the jack-shaft j, from which power is transmitted by 130

chains to the hubs of rear or driving wheels, a suitable differential gear being interposed in the said jackshaft in usual and well-known manner. Thus, in a motor vehicle, the usual objectionable clutch and transmission mechanism is entirely eliminated, and the connections made as direct as would be possible with a steam engine.

A suitable controller, shown as a foot treadle t , is connected with and to operate the brake t' , and also with and to operate the throttles D^2 and T , so that when the said treadle is depressed, it first closes the engine throttles and then applies the brake, and when released, first releases the brake and then opens the engine throttles.

The reservoir D is mounted with a suitable relief or escape valve D^* , to prevent overcharging thereof.

20 As herein shown, the three power cylinder cranks are set respectively, 90 degrees one from another; thus, with the single compression cylinder crank forming a complete balance for the engine. It may, however, in practice, be found desirable under certain conditions to arrange the three working cylinder cranks in position 120 degrees one from another, thereby to obtain more certainty for starting, possibly at a 25 sacrifice somewhat of balancing effect.

My invention is obviously not restricted to the particular embodiment thereof herein shown and described, but may be varied widely within the spirit and scope of the 30 invention.

Claim:

1. An internal combustion two-cycle, self-starting engine comprising a plurality of power cylinders, pistons therein, a compression cylinder and its piston, means to supply fluid under pressure from said compression cylinder to said power cylinders to start the engine and during the operation thereof, reversing means governing the admission of said fluid under pressure, and ignition means connected to said reversing means and adjustable simultaneously with reversing of the engine.

2. An internal combustion two-cycle, self-starting engine having one or more power cylinders each provided with a working piston, a compressed air reservoir, means for maintaining a supply of highly compressed air in said reservoir, means constantly acting during the operation of said engine for supplying to the cylinder a mixture of fuel and highly compressed air from said reservoir for utilization in each forward stroke of the piston, means subsequently to ignite said mixture and cut off said supply, means to exhaust the spent gases and permit return of the piston without necessity of compression, said means including a normally closed exhaust passage near one end of the piston stroke, and a constantly open exhaust pas-

sage near the other end of the stroke, and means for controlling the cut off of said supply means to vary the volume of mixture to be ignited and for varying also said ignition means.

3. An internal combustion two-cycle, self-starting engine comprising one or more power cylinders each with its working piston, a compression cylinder with its piston, means to supply the mixture of fuel and compressed air from said compression cylinder to said power cylinder or cylinders for utilization on each forward stroke, means for varying the cut-off of the said mixture supply, means for exhausting the residual gases on each return stroke, ignition means, and means for varying the timing of the ignition means.

4. An internal combustion two-cycle, self-starting engine having a power cylinder with its piston, a compression cylinder with its piston, means for supplying the mixture of compressed air and fuel from the compression cylinder, to the power cylinder for utilization on each forward stroke, means for exhausting the residual gases therefrom on each backward piston stroke and reversing means for synchronously shifting the time of admission and ignition of the mixture to effect the reversal of said engine.

5. An internal combustion engine having a power cylinder, a compression cylinder, means for compressing the air charge for said power cylinder in said compression cylinder, means for introducing the previously compressed charge into the power cylinder, variable cut-off means for varying the volume of the charge so introduced, while maintaining the compression constant, and means for igniting the mixture.

6. An internal combustion two-cycle, self-starting engine having one or more power cylinders, means for introducing an explosive charge into each power cylinder at each forward stroke of its piston, means for previously compressing the charge before introduction into the cylinder, and variable cut-off means for varying the volume of the charge so introduced without altering the compression thereof.

7. An internal combustion two-cycle, self-starting engine, having one or more power cylinders, a source of compressed air, a source of fuel supply, means for supplying the explosive charge for each cylinder from the said source of compressed air and fuel supply, variable cut-off means for varying the time and duration of admission of said charge, and means for igniting the said charge.

8. An internal combustion two-cycle, self-starting engine, having one or more power cylinders, a source of compressed air, a source of fuel supply, means for supplying the explosive charge for each cylinder from

the said source of compressed air and fuel supply, variable cut-off means for varying the time and duration of admission of said charge, means for igniting the said charge, 5 and means for varying the time of ignition.

9. An internal combustion, two-cycle, self-starting engine comprising a power cylinder and a piston therein, a compression cylinder and its piston for compressing the air charge 10 for the engine, a reservoir to receive fluid under pressure from said compressor cylinder and in communication with said power cylinder, a valve for controlling the delivery of a compressed air and fuel mixture to the 15 power cylinder at each double stroke of its piston, means for varying the action of said valve to control the cut-off of said mixture, ignition means, and means for varying the timing of the ignition means with the timing 20 of said cut-off.

10. An internal combustion, two-cycle, self-

starting engine comprising two or more power cylinders, each with its working piston, a compression cylinder with its piston, means to supply a mixture of fuel and compressed air from said compression cylinder to said power cylinder or cylinders for utilization on each forward stroke, variable cut-off means for varying the time of admission and cut-off of said mixture supply, means 25 for exhausting the residual gases on each return stroke, and ignition means for igniting the supplied mixture of fuel and compressed air.

In testimony whereof, I have signed my 35 name to this specification, in the presence of two subscribing witnesses.

ANDREW L. RIKER.
